UNITED STATES PATENT OFFICE.

WILLIAM JOSEPH BYCRAFT, OF ASHTABULA, OHIO.

PUZZLE.

No. 844,246.

Specification of Letters Patent.

Patented Feb. 12, 1907.

Application filed May 1, 1906. Serial No. 314,617.

To all whom it may concern:

Be it known that I, WILLIAM J. BYCRAFT, a citizen of the United States, and a resident of Ashtabula, in the county of Ashtabula and State of Ohio, have invented a new and Improved Puzzle, of which the following is a full, clear, and exact description.

This invention relates to puzzles or games for amusement purposes, and is especially useful in connection with entertainment devices for children.

The object of the invention is to provide a simple and durable puzzle or game which is of sufficient difficulty of performance to necessitate some little skill and practice, which can be used as a puzzle by an individual or as a game by two or more, and which is easy and inexpensive to manufacture.

The invention consists in the construction and combination of parts described herein-after and more particularly pointed out in the claims.

Reference is to be had to the accompanying drawings, forming a part of this specification, in which similar characters of reference indicate corresponding parts in all the figures.

Figure 1 is a perspective view of my invention. Fig. 2 is a longitudinal cross-section on the line 2 2 of Fig. 1. Fig. 3 is an end elevation, and Fig. 4 is a similar elevation of the other extremity of the invention.

Referring more particularly to the parts, 1 is a tube of glass or other transparent material. The ends of this tube are closed or stoppered by means of plugs 2 of such form that they are adapted to be used as handles, not unlike those of a rolling-pin. These plugs are of some elastic material, such as rubber, and have bosses 3 projecting inwardly into the tube 1 for a purpose set forth hereinafter.

Within the tube is a ball 4, of wood or other suitable material, which is of a diameter slightly less than that of the tube and which consequently can roll freely in the latter.

45 The ball 4 is provided with a recess 5 and a bore 6. This bore 6 is adapted to contain a movable body 7, preferably a small quantity of quicksilver, and is provided with stoppers 8 in the ends thereof to retain this movable

50 body in the bore. The object of this arrangement is to make the rolling movement of the ball 4, under the influence of gravity when the tube is tilted, as erratic as possible.

The tube 1 also contains a second smaller ball or pea 9, which is of such a size that it will easily fit into the recess 5 of the ball 4

and which is of metal or some material heavier than that forming the ball 4, thus giving it greater mobility, due to its increased momentum. The plugs 2 closing the end of the tube 1 are of different colors to enable the operator to distinguish the ends of the puzzle one from the other, and the object of the device is to pass the large ball 4 from one side of the small pea 9 to the other. As the diameter of the ball 4 approximates that of the inner diameter of the tube, the only manner in which this can be accomplished is to roll the large ball 4 over the small one 9, so that the latter enters the recess 5, and thus permits the larger ball to pass over it.

The object of the bosses 3 is to project beyond the small ball 9 when the latter rests against the plug 2, and thus prevents the operator from passing the ball 4 over the pea 9 while the latter is in this position. As the plugs 2 are of an elastic material, they form cushions against the impact of the balls.

It will be understood that the device may be used as a puzzle by an individual, or, if desired, to use it as a game between two or more contestants. Time limits may be set within which each player is to accomplish the solution, or the player requiring the longest time to do this may be considered the loser.

Having thus described my invention, I claim as new and desire to secure by Letters Patent—

1. A device of the class described, comprising a tubular body, a ball adapted to roll in said tubular body and having a recess, a pea within said tubular body adapted to enter said recess to permit said ball to pass therebeyond, and means for distinguishing the ends of said tubular body one from the other.

2. A device of the class described, comprising a tubular body, plugs for the ends thereof forming handles, means for distinguishing the ends of said tubular body, a ball adapted to roll in said tubular body and having a recess, and a pea within said tubular body adapted to enter said recess to permit said ball to roll over said pea.

3. A device of the class described, comprising a transparent tubular body, plugs for the ends thereof forming handles, means for distinguishing the ends of said body, a ball free to roll in said tubular body and provided with a recess, said ball having means for making the movement thereof erratic, and a

2
second ball in said tubular body adapted to enter said recess to permit said first ball to roll over and pass beyond said second ball.

4. A device of the character described, comprising a transparent tubular body, plugs for the ends thereof, said plugs being of different colors to distinguish the ends of the device one from the other, a ball free to roll within said tubular body and provided with a recess, said ball having a chamber with a movable mass therein, a pea within said tubular body adapted to enter said recess, and means for cushioning the impact of said ball against said plugs.
5. A device of the class described, comprising a transparent tubular body, a ball free to roll within said tubular body, and provided with a recess, said ball having a bore

having a movable mass therein and stoppers for the ends of said bore, a pea in said tubular body adapted to enter said recess to permit said ball to roll over said pea, and plugs of elastic material for the ends of said tubular body presenting cushions against the impact of said ball and said pea and forming handles, said plugs having inwardly-projecting bosses adapted to project beyond said pea when the latter rests against a plug.

In testimony whereof I have signed my name to this specification in the presence of two subscribing witnesses.

WILLIAM JOSEPH BYCRAFT.

Witnesses:

JAMES CARROLL,
Mrs. G. MASKELTON.
